ROTARY DRIVE WHEEL TYPE CAN OPENER

Robert E. McLean, Fort Benning, Ga.

Application February 27, 1946, Serial No. 650,436

14. Claims. (Cl. 30—15)

1

This invention relates generally to the class of can openers and pertains particularly to an opener of the type employing a rotary can driving wheel by means of which relative movement is effected between the opener carrying cutting knife and the can top.

The present invention has for a principal object to provide a rotary drive wheel type can opener wherein a new and novel means is employed for effecting a relative movement between the can and the can top penetrating knife simultaneously with the rotation of the driving wheel rotating crank.

Another object of the invention is to provide a can opener of the character stated wherein a novel type of thrust mechanism is employed for effecting the forcible penetration of the can top cutting knife into the can top, which thrust mechanism is of a compact construction and designed to operate in such manner as to facilitate the penetration of the cutting knife into the can top with a minimum of effort.

Another object of the invention is to provide a can opener of the character stated wherein a rotatable toothed driving wheel, designed to effect the turning of the can relative to a cutting knife, forms a part of the thrust mechanism by means of which the can head is forced into engagement with the cutting knife during the preliminary turning of the driving wheel.

Still another object of the invention is to provide an improved can opener of the character stated in which a thrust mechanism is employed for forcing a can top into engagement with a cutting knife, which includes an oscillatable gear segment and a toothed can flange engaging driving wheel which has toothed engagement with said segment to perform the double function of turning the can and simultaneously oscillating the gear segment for the actuation of the thrust mechanism.

Still another object of the invention is to provide in a can opener of the character stated, a novel can rim engaging steadyng means for facilitating the maintenance of the opener in proper position upon the can during the operations of applying the device, cutting out the can top, and reversely actuating the opener to facilitate its removal from the can.

Other objects and advantages of the invention will become apparent as the description of the same proceeds and the invention will be best understood from a consideration of the following detailed description taken in connection with the accompanying drawings forming a part of

2

the specification, with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in elevation of the right hand side of an improved can opener constructed in accordance with the present invention.

Figure 2 is a view in elevation of the left hand or can side of the opener showing the thrust mechanism in lowered or starting position.

Figure 3 is a view in front elevation of the device.

Figure 4 is a view in top plan of the same.

Figure 5 is a vertical section taken substantially on the line 5—5 of Figure 2.

Figure 6 is a transverse section taken on the line 6—6 of Figure 1.

Figure 7 is a view in elevation of the right hand or outer side of the opener equipped with a handle or hand hold means.

Figure 8 is a sectional view taken substantially on the line 8—8 of Figure 7.

Figure 9 is a view in elevation of the lower end and inner side or left hand side of an opener showing a modification of the coupling between the cammed sector plate and the gear sector.

Figure 10 is a sectional view taken substantially on the line 10—10 of Figure 9.

Figure 11 is a view illustrating the application of a mounting bracket to the opener structure for facilitating the mounting of the same on a stationary support.

Figure 12 is a vertical section through a modified form of the construction illustrated in the preceding views showing the modified character of the body plate and the construction of the parts associated with the driving wheel rotating shaft.

Referring now more particularly to the drawings the numeral 10 generally designates, in Figures 1 to 6, inclusive, the body plate of the present improved can opener. This plate, as shown, is relatively long and is designed to be vertically disposed for use.

As best seen in Figures 3 and 5, the body plate is entirely flat or in one plane throughout the major portion of its length, which portion is designated 11, and at one end it is formed to provide a head, generally designated 12, comprising the angularly directed top part 13 and the depending

inner part 14 which is in spaced parallel relation with the body portion 11.

In referring to the positions of the different parts reference will be made to the front and rear of the device and to the inner and outer sides thereof.

In referring to the front and rear of the device reference will, of course, be had to the parts of the device which are respectively nearest to and farthest from the user of the device when it is set up and the inner and outer sides refer respectively to the left hand and right hand sides or the side of the device upon which the can is positioned and the side remote from the can.

At its lower end the body plate is formed, adjacent to the inner edge thereof, with the inwardly directed can rest or foot 15.

In line longitudinally of the body plate with the center of the can rest 15, the body portion 11 is provided with the longitudinally extending elliptical bearing opening 16 and above this opening and opposite to the portion 14 of the head are the merging openings 17, the purpose of which will be hereinafter disclosed.

Also in line longitudinally of the body plate with the bearing opening 16 and the center of the can rest 15, is the fixed rivet 18 which extends inwardly or to the left of the body plate as shown in Figure 5 and upon which are oscillatably supported the cammed sector plate 19 and the gear sector 20. These units are, in addition to being oscillatably supported upon the pivot rivet 18, securely fastened together in the presently described embodiment of the invention by the rivet 21 and the sector plate 19 is disposed between the body plate and the gear sector as shown.

The gear sector has the arcuate series of gear teeth 22, the arc upon which said teeth are laid out, being struck from a point or center eccentric to the pivot rivet 18, which center is rearwardly of the rivet.

The cammed plate 19 has formed therein the arcuate opening or slot 23 which has the inner and outer radii 24 and 25 respectively which are concentric with the arc of the gear sector 20.

At the rearward end of the cam slot 23 the inner radius edge 24 is modified to provide the raised bearing shoulder 26 which is formed on a true radius on the axis of the pivot rivet 18 and this radius for the bearing shoulder 26 is slightly greater than the radius between the axis of the pivot rivet 18 and any point of the inner radius 24 of the cam slot of the cammed sector 19.

Extending through the bearing slot 16 is the arbor 27 which carries upon the inner or left hand side of the body plate, the journal 28 and inwardly from the journal, the combined can rim engaging driving wheel and thrust mechanism operating gear 29.

Upon the outer side of the arbor 27 is mounted the spacer sleeve 30 upon the inner end of which is carried the collar 31 which overlies the opening 16 and is adapted to engage the outer side of the body plate to maintain the arbor and adjacent parts connected therewith, in proper position with respect to the body plate and the elements 19 and 20.

Upon the outer end of the arbor 27 is fixed the crank 32 which is here illustrated as being in the form of a thumb and finger lever.

As shown in Figure 5 the diameter of the journal 28 is slightly less than the width of the cam slot 23 and the journal 28 is positioned within this cam slot and contacts the outer radius 25 of the slot but is spaced from the inner radius

thereof throughout the entire length of the latter with the exception of the portion where the bearing shoulder 26 is formed.

As shown in Figure 2 the high point of the bearing shoulder 26 is slightly beyond the rearward end of the row of teeth 22 forming a part of the gear sector 20 whereby it will be understood that when the journal 28 is in the rearward end of the cam slot 23 where it will be closely engaged between the outer radius 25 and the shoulder 26, the teeth of the gear wheel which, in all other positions of these parts are in mesh with the teeth 22, will be out of engagement with the teeth 22 of the gear sector and consequently free rotation of the wheel 29 may be maintained.

The numeral 33 generally designates the head carried can rest. As shown most clearly in Figures 4 and 6 this unit is of substantially U-shaped form and comprises the central portion 34 and the side portions or wings 35 which are turned at right angles to the portion 34.

The overall width of the can rest 33 is the same as that of the body plate 10 and accordingly, as shown in Figure 4, the depending portion 14 of the head 12 is of sufficiently reduced width to be snugly received between the wings 35 and thus when the can rest is in position it will not project beyond the front and rear edges of the body plate. Upon the outer side of the downwardly extending portion 14 of the head there is fixed, in the vertical plane of the arbor 27, the knife or cutter 36. This part and the can rest 33 are secured by means of the rivets 37 which pass through the intervening head portion 14. By the provision of the openings 17 in the body plate, the placement and securing of these rivets in fixed position is readily accomplished.

The lower or cutting end of the cutter blade 36 is sufficiently blunt to assure adequate traction of the teeth of the can driving wheel 29 with the under edge of the rim or flange of a can. This is accomplished by wedging the end and rim or flange of a can between the cutting end of the cutter blade and the teeth of the wheel 29.

While the can driving wheel and the journal 28 have been described as being a part of the arbor 27 it is contemplated as being within the scope of the present invention to make these parts separate and fix them in a suitable manner to the arbor 27 if such practice is preferable.

In a modified construction shown in Figures 7 and 8 the can opening device generally designated 38 and which may be a duplicate of the embodiment illustrated in Figures 1 to 6 inclusive, is shown equipped with a handle 39. This handle may be secured to the body plate 10 by suitably extending the pivot rivet 18a and using a second countersunk rivet 40 as shown in Figure 8. The use of this handle 39 with the unmounted embodiment of the opener structure, is, of course, optional.

Figures 9 and 10 illustrate a modification of the coupling means between the cammed plate and the gear sector, such modified coupling reducing placing the fixed rivet 21 as shown and described in connection with the first embodiment.

In this modified construction of the thrust mechanism the body plate is designated 18c and is essentially the same as the body plate 10 and is fixed thereto in the same position as the pivot rivet 18, to extend inwardly from the body plate, is the similar pivot rivet 18c.

The cammed sector plate is designated 19a and is oscillatably mounted upon the rivet 18c as shown in Figure 10.

The modified gear sector is designated 20a and this also is oscillatably mounted on the pivot 18c but is designed to have limited independent oscillation from the plate 19a.

The plate 19a has struck therefrom and extending inwardly the stop 44 and the gear sector 20a has formed therein the opening 45 in which the stop 44 is positioned. As shown in Figure 9 the width of the opening 45 is greater than the width of the stop 44 and consequently the gear sector 20a may oscillate slightly upon the pivot 18c independently of the cammed plate 19a.

The gear sector 20a is pressed or otherwise suitably formed in that portion through which the rivet 18c extends, to form the offset 46 which extends inwardly away from the plate 19a and thus provides between this plate and the gear sector, the shallow chamber 47 in which is housed a spring 48. The spring 48 is turned around the body of the pivot rivet 18c and one of its ends is turned outwardly and secured in a suitable opening 49 in the cammed plate 19a while the opposite end is turned inwardly and secured in a suitable opening in the gear sector as indicated at 50.

The spring 48, which is substantially U-shaped, is of light tension and is so biased that one end thereof is normally urged away from the other end. It will thus be seen that the gear sector 20a will be constantly urged to oscillate rearwardly with respect to the adjacent cammed plate so that when the toothed driving wheel, not shown in Figures 9 and 10, is in the rearward end of the cam slot of the plate 19a the toothed plate will be instantly moved into the proper position for the engagement of its teeth with the teeth of the driving wheel as soon as reverse or counterclockwise rotation is imparted to the driving wheel for the purpose of releasing a can from the opener.

In Figure 11 the numeral 41 generally designates an extension arm secured to the lower end of the opener body plate, here designated 10b, by the pivot rivet 18b and a countersunk rivet 40a, corresponding to the rivet 40 shown in Figures 7 and 8. This extension arm forms part of a conventional type of wall mounted supporting bracket such as is shown in my prior Patent No. 2,351,581 of June 13, 1944.

There is also shown in Figure 11 a crank arm 42 which is more suitable for use with the can opener when the latter is mounted upon a wall bracket such as that shown, than the thumb and finger operated crank 32. This crank arm 42 is, of course, secured, in place of the crank 32, to the outer end of the arbor 27a and it carries at the end opposite from the arbor, the knob 43, by which the crank may be grasped for the purpose of turning the can driving wheel.

The numeral 10d, in Figure 12, generally designates another body form for use with the thumb and finger crank 32a. As shown, this body plate 10d is offset at 51 to permit insertion of a spacer washer 52 between the body and the cammed sector 19b.

The handle 32a is formed integrally with the shaft 27b which is of polygonal cross section and which extends, like the arbor 27, through an elliptical opening 16a formed in the body plate.

Upon the outer side of the body plate the shaft 27b carries a spacer 53 and between this spacer and the spacer 52 is mounted upon the shaft the journal 28a which rides in the bearing slot or opening 16a in the same manner as a portion of the arbor 27 rides in the bearing slot 16. The journal 28a is of larger diameter than the arbor

27 and consequently the bearing opening 16a will be of corresponding width and larger than the opening 16.

5 A second journal is mounted upon the shaft 27b upon the inner side of the spacer 52, this second journal being designated 28b and being positioned within the cam slot 23a of the plate 19b.

Secured to the inner end of the shaft 27b is the pinion gear 29a which meshes with the teeth 10 of the gear sector 20b and fixed against the pinion gear 29a is the toothed driving wheel 29b which lies in a plane inside the gear sector 20b as shown and is adapted to engage the under side of the can rim.

15 The several units as shown upon the shaft 27b are assembled in proper order after the spacer 53 is positioned on the shaft and the shaft is extended through the bearing opening 16a, after which the inner end of the shaft is suitably swaged to lock the several parts in position thereon. Since the shaft is of polygonal cross section the parts will be maintained in position against turning.

20 As will be readily apparent the extension arm 41 or the handle 39 may be used, if desired, in connection with the structure illustrated in Figure 12.

25 Although the device here illustrated is shown as having a cammed quadrant of substantially ninety degrees, it is to be understood that this 30 quadrant may be of any desired number of degrees less than illustrated, the pitch of the cam and the corresponding pitch of the toothed gear sector or gear segment, being increased to effect the required vertical movement of the can driving wheel.

35 The operation of the present device is as follows:

40 If the handle or crank 32, 32a or 42 is not in the extreme counterclockwise position, it is first 45 rotated to such position which action will bring the cammed sector plate rearwardly so that the journal of the can driving wheel will be in the forward end of the cam slot 23 or 23a and the can driving wheel will be lowered with respect to the cutter.

45 The unmounted embodiment of the invention, shown in Figures 1 to 6 inclusive and Figure 12, is then installed on the can by hanging the cutter blade over the rim or bead of the can. When 50 in this position the can rest 33 will limit the oscillation of the device on the can and the inner end of the foot rest 45 will position against the side of the can.

55 The crank is then rotated clockwise and at the start of such rotation, the teeth of the can driving wheel 29 or gear 29a being in mesh with the teeth of the toothed gear sector and riding thereon, such gear sector and the adjacent quadrant plate will be oscillated counterclockwise.

60 As the gear sector turns beneath the rotating gear wheel its eccentric form, with respect to the pivot center of the rivet 18 or corresponding rivets 18a, 18b or 18c, will raise the can driving wheel or gear wheel and thus force the can head into engagement with the knife, causing the knife to penetrate the head.

65 When the cutter has penetrated the can head a predetermined depth, the teeth of the gear wheel will run out of mesh with the teeth of the 70 toothed gear sector or segment and the journal 28 or 28b will seat on the shoulder 26 of the cammed quadrant.

75 Continued clockwise rotation of the operating handle feeds the device about the can until the end of the can is completely cut out.

Due to contact between the journal 28 or 28b with the bearing seat 26, counterclockwise rotation of the operating handle will cause the teeth of the can driving wheel 29 or of the pinion gear 29a to reengage with the teeth of the toothed sector and the operating handle is rotated counterclockwise to its extreme position, as shown particularly in Figure 2.

During such counterclockwise rotation of the operating handle or crank, the can rest 33 also prevents the device from tilting or oscillating on the can. Preferably, the operator exerts a slight downward pressure on the top of the device when rotating the operating handle counterclockwise. The device may then be lifted from the can.

Operation of the embodiment shown in Figure 11 is the same, except that the can is held with its upper end against the lower end of the cutter blade until the can driving wheel, not shown, arrives at its uppermost position during clockwise rotation of the operating handle 42. The can is again held as the operating handle 42 is rotated counterclockwise to release the can from the device after the end of the can has been cut out.

The outer radius 25 of the cam slot 23, and corresponding parts of the other embodiments, maintains the teeth of the can driving wheel 29, or of the gear pinion 29a, in substantially full depth engagement with the teeth of the gear sector at all times that the teeth are in mesh. The toothed gear sector controls the upward movement of the can driving wheel, whereas the outer radius of the cam slot of the quadrant controls the downward movement of the can driving wheel.

The operation of the modified thrust mechanism shown in Figures 9 and 10 will, it is believed, be readily obvious. As will be apparent, when the clockwise rotation of the operating crank is begun the gear sector 20a will first be oscillated against the tension of the spring 48 until such oscillation is checked by the stop 44 after which the quadrant 19a and the gear sector will move together until the journal 28 moves into position on the shoulder 26. At this time the driving wheel or gear will run out of engagement with the teeth of the gear sector and the driving wheel may be rotated freely. As soon as counterclockwise movement is imparted to the driving wheel, the action of the spring tending constantly to move the gear sector counterclockwise, causes the adjacent end tooth of the gear sector to move into contact with the teeth of the can driving wheel or gear pinion so that immediate engagement between these parts is effected. In other words, the spring operates constantly to maintain the teeth of the driving wheel or pinion and the teeth of the gear sector constantly in contact in the nature of a ratchet.

The head 12 constructed in the manner herein disclosed, has sufficient resiliency to permit the cutter blade to be forced laterally away from the can driving wheel sufficiently, when necessary, as when the cutter is passing the seam of the can, to facilitate operation.

From the foregoing it will be seen that a can opener constructed in accordance with the present invention is of compact form and makes possible the operation of puncturing the can top with the cutting knife and the rotation of the can relative to the cutter, by the manipulation of a single crank member. The device also provides novel means for effecting the return engagement of the gear element when it is desired to remove the device from the can, without the em-

ployment of movable parts in addition to the can driving wheel and the oscillatable thrust mechanism.

While in the structure shown in Figure 12 there have been illustrated two separate elements 29a and 29b described respectively as a gear pinion and a toothed can driving wheel, it will be readily recognized that these elements may be made as a single unit and also that the teeth of the part now described as the pinion gear 29a may be formed in the same shape as the teeth of the can driving wheel so that a single wheel may be provided having teeth like those shown in Figure 2 for the wheel 29, the outer ends of which engage the teeth of the gear sector 20b while the inner ends engage the can rim to effect the desired turning of the can. Accordingly, in the claims the wheel will, in these two embodiments be understood as embracing both the toothed member and the member which engages the can rim to effect the movement of the can.

It will also be readily apparent that the crank 42 may be used in substitution for the thumb and finger crank 32a of Figure 12 by establishing the proper coupling between the shaft 27b, separated from the crank 32a, and the crank 42.

I claim:

1. A can opener of the rotary drive wheel type, comprising a body plate, a cutting knife carried thereby, a toothed unit supported on the body for rotation and for rectilinear movement toward and away from the knife, said unit being designed for operative driving connection with the under edge of a can rim, means for rotating said unit, a thrust unit oscillatably supported on the body and having an eccentric arcuate portion, said rotary unit having positive rolling driving connection with and being adapted to be supported on said arcuate portion, and means for freeing the rotary unit from said positive driving connection for free rotation upon the turning of the thrust unit to a predetermined extent in one direction, the thrust unit functioning upon turning in the said one direction to move the rotary unit toward the knife.

2. A can opener of the rotary drive wheel type, comprising a body plate, a cutting knife carried thereby, a toothed wheel rotatably supported on the body plate for rectilinear movement toward and away from the knife, the wheel being designed for peripheral driving connection with the under edge of a can rim, means for rotating the wheel, a thrust unit for effecting the positive shifting of the wheel toward the knife and comprising a body oscillatably supported upon the body plate and having an eccentric arcuate portion, means forming a positive rolling driving connection between said wheel and the arcuate portion of the thrust unit plate, said thrust unit plate being beneath and positively supporting said wheel while the wheel is in driving connection therewith, and means for disconnecting the driving connection between the wheel and the thrust unit plate for free rotation of the wheel, upon the turning of the unit to a predetermined extent in a direction to effect movement of the driving wheel toward the knife.

3. A can opener of the rotary drive wheel type, comprising a body plate, a cutting knife carried thereby, a toothed wheel rotatably supported on the body plate for rectilinear movement toward and away from the knife, said wheel having peripheral teeth adapted to engage the under edge of a can flange to impart rotary motion to the can, a thrust member for imparting movement to the wheel toward and away from the

70
75

knife and comprising a plate pivotally mounted upon the body plate, a gear sector connected with the thrust plate beneath said wheel and having teeth arranged eccentric to the center of oscillation of the thrust plate, said wheel teeth being adapted for driving connection with the gear sector teeth, means for rotating the wheel to effect oscillation of the thrust plate, the wheel when rotated in one direction riding over and being supported by the gear sector and oscillating the thrust plate in one direction and moving the wheel toward the knife, the thrust plate when oscillated a predetermined extent in the said one direction moving the gear sector out of toothed connection with the wheel, and means for bringing the toothed sector back into connection with the wheel upon opposite rotation of the wheel.

4. A can opener structure of the character stated in claim 3 in which said last means comprises a journal rotatable with the wheel and means for establishing frictional contact between the journal and a portion of the thrust unit plate upon separation of the wheel from the gear sector.

5. A can opener of the character stated in claim 3 in which the last mentioned means comprises a spring coupling between the gear sector and the thrust unit plate and a positive coupling permitting a limited relative oscillatory movement between the gear sector and the thrust unit plate, the spring being biased to shift the gear sector in a direction to effect reestablishment of the toothed connection between the sector and the toothed wheel upon reverse rotation of the wheel after the wheel has been shifted to the stated predetermined extent toward the knife.

6. A can opener of the rotary drive wheel type, comprising a body plate, a cutting knife carried thereby, a toothed rotatably mounted wheel carried by the body for movement toward and away from the knife, said wheel being designed to have its teeth operatively connected with the under edge of a can rim to effect turning of the can, means for rotating the wheel, a thrust unit for effecting movement of the wheel toward and away from the knife comprising a plate sector pivotally mounted upon the body plate and having an eccentric arcuate slot, a journal concentric with the wheel and adapted to rotate therewith and lying within said slot, an eccentric gear sector supported for coaxial oscillation with the sector plate and having toothed connection with said wheel, the gear sector being of less arcuate extent than the slot whereby upon oscillation of the sector plate to a predetermined extent in one direction to effect movement of the wheel toward the knife, the wheel will be freed from the gear sector, and means cooperating with the journal for effecting reengagement of the wheel with the gear sector upon turning of the wheel in one direction following the separation of the wheel from the gear sector.

7. A can opener of the character stated in claim 6 in which the last means comprises an elevated portion of the inner radius of the slot with which the periphery of the journal frictionally engages.

8. A can opener of the rotary drive wheel type, comprising a body plate, a cutting knife carried thereby, a toothed wheel rotatably supported on the body for movement toward and away from the knife, said wheel being designed to have the teeth thereof operatively engaged with the under edge of a can rim to impart rotary motion to the can, means for rotating the wheel, a journal

coupled with the wheel for rotation therewith, a thrust unit for effecting movement of the wheel toward and away from the knife and comprising a sector plate, a pivotal coupling between the sector plate and the body plate for oscillation of the sector plate in a plane paralleling the body plate and transversely of the rotary axis of the wheel, an arcuate slot in the sector plate in which said journal positions, the journal having peripheral contact with the outer radius of the slot and being free of contact with the inner radius of the slot, the slot being eccentric to the oscillation center of the sector plate, a sector gear supported for oscillation with the sector plate, the gear having teeth concentric with the slot and adapted to be engaged by the teeth of the wheel, the arcuate extent of the gear teeth being less than the extent of the slot whereby upon oscillation of the sector plate in a direction to effect movement of the wheel toward the knife the wheel teeth will run free of the gear teeth, and a shoulder formed upon the inner radius of the slot at a point to frictionally engage the periphery of the journal when the wheel teeth run free of the gear teeth.

9. A can opener structure of the character stated in claim 8 in which the gear sector is supported for independent oscillation from the sector plate, a coupling means between the gear sector and sector plate for limiting oscillation of the gear sector relative to the sector plate and a spring means coupling the gear sector and sector plate and normally urging oscillation of the gear sector toward the end of the slot in which the shoulder is formed.

10. A can opener of the rotary drive wheel type, comprising a relatively long flat plate adapted to be vertically disposed for use, the plate having a head at its upper end comprising a horizontal, lateral extension and a terminal depending extension in spaced parallel relation with the body of the plate, a can rim engaging driving wheel rotatably supported by the plate for limited movement longitudinally thereof toward and away from the head, means for rotating said wheel, a thrust mechanism forming an operative coupling between the wheel and the plate for effecting movement of the wheel toward and away from the head upon clockwise and counterclockwise rotation of the wheel, a knife secured to said depending extension for coaction with the wheel and disposed in a plane offset from the side of the wheel remote from the plate, a can rim engaging rest comprising a substantially U-shaped member having a straight central portion and spaced parallel right angularly extending end portions, the central portion of the rest being disposed across the depending portion of the head and the right angularly extending end portions of the rest extending toward the body plate whereby the bottom edges thereof lie in a plane extending across the planes of the knife and wheel, said end portions being free of connection with the body plate and means securing the rest to the head.

11. A can opener of the character stated in claim 10 in which said securing means comprises rivets passing through the central portion of the rest, the depending portion of the head and the knife blade.

12. A can opener of the character stated in claim 10 in which the knife blade comprises a flat blade member disposed upon the side of the depending portion of the head adjacent to the body plate, the central portion of the can rest

11

being disposed across the side of said depending head portion remote from the body plate, and securing rivets passing through the knife plate, depending head portion and central can rest portion to secure said parts as a unit.

13. A can opener of the character stated in claim 10, with an angularly directed foot portion formed integrally with the lower end of the body plate to extend from the side thereof adjacent to the depending portion of the head for coaction with said rest.

14. A can opener of the character stated in claim 10, with a rigid handle member secured to

12

and across a side face of the body plate at the lower end thereof to extend substantially perpendicular to the length of such plate.
